US0D1093994S

(12) United States Design Patent (10) Patent No.: US D1,093,994 S
(45) Date of Patent: * Sep. 23, 2025

(54) PAN

(71) Applicant: Lagom Kitchen Co., Los Angeles, CA
(US)

(72) Inventors: Melinda Olsen, Los Angeles, CA (US);
Amir Tehrani, Los Angeles, CA (US);
Christopher Santone, Brooklyn, NY
(US); Hlynur Atlason, New York, NY
(US)

(73) Assignee: Lagom Kitchen Co., Los Angeles, CA
(US)

() Term: 15 Years

(21) Appl. No.: 29/921,817

(22) Filed: Dec. 19, 2023

Related U.S. Application Data

(63) Continuation of application No. 29/817,427, filed on Dec. 1, 2021, now Pat. No. Des. 1,015,800.

(57) CLAIM

The ornamental design for a pan as shown and described.

DESCRIPTION

FIG. 1 is a top, front perspective view of a pan;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the pan form no part of the claimed design.

1 Claim, 4 Drawing Sheets
